Fig. 1

Fig.6

FIG. 1 is a top, front perspective view of my new design of a safe for valuables or the like.

FIG. 2 is a top, front perspective view of the safe of FIG. 1 with the door in an open position.

FIG. 3 is a front elevational view.

FIG. 4 is a side elevational view as seen from the right in FIG. 1, the other side view being a mirror image thereof.

FIGS. 5 and 6 are top and bottom plan views, respectively, of same safe.

I claim:

The ornamental design for a safe for valuables or the like, as shown and described.
